UNITED STATES PATENT OFFICE

LUTHER S. MUNSON, OF WEST RIVERDALE, MARYLAND

BUILDING WALL

Application filed July 11, 1929. Serial No. 377,503.

The present invention relates to improvements in a building wall formed essentially of a plurality of interengaged blocks or tiles and interposed mortar or like cementitious material.

One object of the invention is to provide a block or tile element configured with complementally formed end portions of a character to permit adjacent elements in a wall 10 to interfit to form a composite wall structure of superior value in reacting against both vertical and lateral stresses.

Another object of the invention is to provide a simple and inexpensive tile adapted 15 to be engaged with other similar units in a wall construction, the formation of the tile units being such that the labor required in the building of a wall therefrom is reduced to a minimum.

20 A further object is to provide a wall formed of a plurality of similar tile units tied together through their horizontal joints by means of the compressive strength of the tile material alone, and through their vertical 25 joints by a minimum of mortar bedding in the neutral axis of the vertical joints whereby the transverse components of lateral stresses impressed on the wall are principally absorbed in compression of the mortar instead 30 of by the shearing strain of the mortar and of the tile material which characterize wall constructions prior to my present invention.

Further objects and advantages will sufficiently appear from the description herein- 35 after of the invention in one form of embodiment taken in connection with the accompanying drawings, wherein

Fig. 1 is a fragmentary elevational view 40 of a wall constructed according to the present invention;

Fig. 2 is a horizontal sectional view thereof, taken on the line 2—2 of Fig. 1; and

Fig. 3 is a perspective view of one of the tile units.

45 It is well known that the burned clay or concrete material universally used in the manufacture of building tiles has a high value in compression, and a relatively very low value in both tension and shear. The mortar 50 commonly employed to bind tile units to-

gether in a wall has likewise a very low strength in tension and shear, and in addition, a much lower compression value than that of even low grade tile material.

It will be apparent, therefore, that the vertical compression strength of a wall constructed of superposed tile or block units having layers of mortar in the horizontal joints formed by meeting horizontal tile faces will be limited by the compression strength of the 55 mortar material. For example, a wall so constructed of tiles whose material has a compression value of five thousand (5,000) pounds per square inch (a typical value for good grade tile), and whose mortar bedding 60 has a compression strength of one thousand (1,000) pounds per square inch (a generous figure for high grade mortar), will break down under a vertical load in excess of one 65 thousand (1,000) pounds per square inch. 70

One object of my present invention is to provide a wall, the composite vertical compression strength of which will be equal to the compression strength of its individual tile components. I accomplish this object by 75 dispensing with the usual layers of mortar in the horizontal joints, disposing the mortar instead only in the vertical joints formed between meeting vertical tile faces, in a position and for a purpose which will be hereinafter more fully explained.

80 Fig. 1 shows to advantage the method of constructing a wall to attain this object. It will be noted that both full and half length units, designated respectively A and B, are 85 employed to produce the customary staggering of horizontal joints in adjacent vertical tiers in a well understood manner. Because of the recessed and extended end portions of the tiles, described in detail hereinafter, a 90 special order of placing the units in the wall, as indicated in Fig. 1 by the numerals on the units, is to be preferred. I have found that by following the order designated a wall structure may be built up without the necessity of sliding any tile unit into place between two previously positioned units, thus 95 conducting materially to the ease and dispatch with which the wall may be erected.

100 It is apparent that maximum efficiency in

resisting vertical stresses will be attained in a wall composed of tiles whose meeting horizontal edges contact throughout their whole extent with the adjoining tile, and that this 5 degree of efficiency will be realized in proportion as the horizontal edges of the tiles are accurately formed. While it is impossible in commercial tile production to economically make tiles with horizontal edges of mathematical precision, it has been found that the 10 cutting of a reasonably accurate horizontal edge on clay blocks is entirely compatible with economical commercial production, and that such reasonably accurate edges make possible 15 horizontal joints which will have a very much higher value in carrying vertical loads than is attainable when even the highest grade of mortar bedding is used in the horizontal joints.

20 If vertical load were the only stress necessary to be borne by a wall in practical use, then maximum strength in vertical compression would be the sole desideratum in wall constructions, and this object might well be 25 attained by merely eliminating the mortar from the horizontal joints and disposing it instead only through the vertical joints. The problem of producing a wall of maximum efficiency is, however, further complicated by 30 the impression in practical use upon the composite wall of lateral loads of constantly varying direction and intensity, as typified by direct wind pressure exerted on the outside of a building, and the differential of atmospheric pressure on the inside and the partial 35 vacuum pressure on the outside of a building on account of eddy currents in the air. It is well known that these partial vacua frequently drop to very low pressures during 40 tornadoes and cyclones, being sometimes sufficiently low to cause the wall to fail and disintegrate outwardly against the vacuum pressure. Unequal expansion of the inside and outside wall surfaces induced by fire and 45 climatic conditions, and the impressed force of fire extinguishing streams of water, are other examples of heavy lateral stresses which an efficient wall must be capable of withstanding.

50 It will be appreciated that lateral stresses impressed against the wall in a direction normal thereto, as indicated by the arrow in Fig. 2, will be resisted partly by compressive strain in the side faces of the tile units, and 55 partly by transverse components passing through the vertical joints of adjacent tiles. In an ordinary wall construction having mortar bedding throughout the entire meeting vertical faces of adjacent tiles, these transverse components assume the character of 60 shearing strain in the mortar bedding. As has been pointed out hereinabove, the shearing value of even high grade mortar is relatively very low, and such walls therefore, 65 fail under comparatively moderate lateral

stresses. In wall constructions provided with interfitting tongue and groove portions in the vertical joints, these transverse components take the form of shearing strains in the tile material itself, and, as will be readily realized, the shearing value of the necessarily reduced depth of tile material in a tongue and groove arrangement will also be relatively low, causing the wall to fail by reason of the shearing off of small sections of the edges of 70 the tongues and grooves.

75 Fig. 3 of the drawings shows a tile unit constructed according to the principle of my present invention. This unit consists essentially of a hollow body open at opposite ends 80 and formed of similar front and back faces 12, which are conveniently rectangular in plan and are preferably connected approximately midway their ends of a substantial integral reinforcing web 13. The face portions 12 are further connected by opposite end portions of dissimilar but generally complementary form. One end portion is indented to provide a V-shaped recess 14, while the opposite end portion is extended to form 85 an inverted V-shaped protrusion 15 of the same angular measurement as the recess 14. The apex of the protrusion 15 is depressed to provide an end groove or channel 16, and it should be noted that the tile material in the 90 rear of the channel 16 is preferably internally extended in the direction of the depression forming the channel, so that the material of the end portion 15 is in no way weakened by 95 the channel 16.

100 The manner of joining adjacent vertical tiers of tile is shown to advantage in Fig. 2, and consists of interengaging the complementary end portions 14 and 15 of adjacent tile units to secure adjacent tiers against relative 105 displacement. It will be apparent that when so associated the channel 16 and the central portion of the recess 14 of abutting tile ends will define a continuous cylindrical or cylindroidal cavity, co-extensive in length with the 110 height of the vertical tiers. Into this cavity mortar 17, in a plastic state, is run, which, when set, forms a vertical column in the joints formed by abutting vertical tiers of tiles. The natural inequalities on the proximate portions 14 and 15 of adjacent tile units 115 hold them spaced as indicated by arrows 19 in Fig. 2. Spacing is also assured by interpositioning of the mortar column between 120 said adjacent tile units.

125 When a wall so constructed is subjected to lateral stresses it will be apparent that such stresses will be resisted by compressive strain horizontally of the side faces 12 of the tile units, and by other horizontal components passing through the line of juncture of abutting tile ends, i. e., the vertical column of mortar bedding 17. Since this mortar is disposed only in the neutral axis of the vertical joints about which these components revolve, 130

it will be affected by these components only to a relatively small extent. It will be appreciated also that these components will be resisted largely by compressive strain of the 5 mortar, thus utilizing to the fullest extent the mortar's reaction capacity of highest value. The components passing through the vertical joints will also be resisted in part by shearing strain in the end portions 14, 15 of the tiles 10 themselves, this strain appearing first at the extreme outer corners of the recessed end wall 14, and to provide increased strength at these points and consequently greater resistance to shearing stresses, these corners are rounded 15 off, as shown at 18 in the drawings.

It is to be understood that the invention hereinbefore described is capable of other and further forms of embodiment, all of which are to be considered within the scope 20 of the appended claims, insofar as they exemplify the principles of the present invention.

What is claimed is:

1. In a wall construction formed of interfitting tile elements having complementally 25 formed end portions of substantially V-shaped protrusions and recesses, the apex of each protrusion having a channel therein, a column of mortar positioned in each of said channels and impinging against the adjacent 30 tile element, the remainder of the complementally formed end portions being spaced.

2. In a wall including hollow tile elements arranged in superimposed relation, each of 35 which is provided with a terminal depression converging from the sides of the latter, the opposite end of each element having inclined lateral faces complementing the contour of the depression to house a portion of said opposite end, bounded by the inclined lateral 40 faces of one tile, completely within the depression of an adjacent tile, but spaced therefrom, and a column of mortar interposed between the proximate faces of the tile elements.
